(57) CLAIM

The ornamental design for a shoe outsole design with bowknot pattern as shown and described.

DESCRIPTION

FIG. 1 is a perspective view of a shoe outsole design with bowknot pattern showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is another perspective view thereof.

FIG. 9 is an enlarged view of circled portion 9 in FIG. 8 thereof; and,

FIG. 10 is an enlarged view of circled portion 10 in FIG. 3 thereof.

The broken lines throughout the drawing figures depict portions of the shoe outsole design with bowknot pattern that form no part of the claimed design.

The dot-dash broken lines depict the boundaries of the FIGS. 3, 8, 9 and 10 enlargement that forms no part of the claimed design.

1 Claim, 10 Drawing Sheets
